IMPROVED BURRING MOTION FOR
TREATING WOOL AND OTHER TEXTILE
FIBERS

Antoine Thibaut, Tourcoing, France

Application June 30, 1933, Serial No. 678,510
In France July 8, 1932

1 Claim. (Cl. 19—84)

The present invention relates to the extraction of burrs from textile fibers on carding machines, and more particularly the extraction of burrs on cards for wool, especially worsted.

5 It is known that the object of the burring operation is to eliminate vegetable waste, straw, burrs, etc. generally known as burrs.

This operation is carried out on carding machines by an assembly of separating and cleaning members forming the burring motion of the 10 cards, and generally comprising a crushing roller and a burring roller.

With a view to increasing the refining action 15 of the burring operation according to the nature and type of fibers treated, various arrangements have been put forward generally comprising a certain number of crushing rollers and/or burring rollers arranged differently according to the ideas of the designer.

20 Arrangements have also been put forward which comprise a number of successive burring devices operating on the material under treatment and driven at successively higher speeds.

A more special arrangement has been evolved, 25 which is known as the "Morel" burring motion, placed in front of the carding cylinder or cylinders and employed more particularly on worsted cards. The "Morel" burring motion is disclosed in French Patent No. 254,583, of March 10, 1896 and the addition thereto of 1898; and also disclosed in British patent to Morel, No. 28,734, of 30 1897.

These "Morel" burring motions are formed essentially by the combination of a bristle roller, a 35 crushing roller which receives the material from the bristle roller, and a burring roller.

This "Morel" burring device separates the work of burr removal into a distinct operation independent of the carding, and it comprises a bristle roller which is made much too flexible to exert 40 any carding action. It is placed between a licker in or a breast roller and the carding cylinder and exerts no carding action.

In spite of the known advantages of the 45 "Morel" burring motion it still possesses certain disadvantages. In particular it has to be adjusted carefully according to the quality or the origin of the fibers to be treated, it does not extract the light or heavy impurities sufficiently when the 50 working speed adopted is too slow or too fast, while a certain quantity of good fibers, varying with the working speed, is carried away with the impurities.

The object of the present invention is to remove 55 the disadvantages of this type of Morel burring

motion, and it is based on the following observations.

When these devices are working at high speed, the heavy impurities carry along with them a greater quantity of good fibers than when the 5 extraction of burrs is extracted at a slower speed. Moreover, the mechanical impact at high speed of the blades of the burring roller on the fragile and heavy impurities most frequently causes them to be broken up into small fragments instead of 10 being thrown out of the card, and these small fragments then remain in the material treated during the carding operation.

Moreover, it has also been observed that when a Morel motion is working at slow speed, it does 15 not separate out the light impurities.

Now the object of the invention is to subdivide the work performed by a Morel burring motion. With this object in view the invention consists in an improved Morel burring motion which is characterized by the feature that it comprises two or more bristle rollers, two or more crushing rollers and two or more burring rollers, these members being arranged in two or more groups arranged 20 in sequence and each comprising a bristle roller, 25 a crushing roller and a burring roller, while each successive group works at a suitable increasing speed, this speed being slow in the case of the first group, faster for the second, and so on.

By means of these improvements the various 30 types of impurities are extracted successively by the subdivided operation of the various groups. Only a very minute quantity of impurities is left in the product undergoing the carding treatment, and the quantity of good fibers removed with the 35 impurities is also greatly reduced.

These results are obtained by the fact that, during the passage through the first group, the heaviest impurities (burrs, small nuts, fragments of skin, etc.) on account of their weight and/or 40 their size, are extracted without being broken up by the blades of the burring roller turning at slow speed, while during the passage of the second group, the lighter impurities (straw, splinters, etc.) which still remain are, on account of their 45 small weight, extracted by the more rapid motion of the members of the second group, and so on.

In order to make the invention clearly understood and by way of constructional example, one embodiment is hereinafter described and is illustrated in the accompanying drawing, which shows a side elevation of a carding machine having the improved burring motion fitted thereto.

In the drawing, 1 is a breast roller and 2 the carding cylinder or main swift.

Between these two members, and in place of the usual separating and cleaning members, or again in place of a Morel burring motion of known type, is mounted the improved Morel burring motion formed, according to the invention, by a bristle roller 3, a crushing roller 4 with its burring roller 5, a bristle roller 3', a crushing roller 4' and its burring roller 5'. 6 is a transferring roller conveying the cleansed fibers to the cylinder 2, and 10 7 and 7' are the troughs receiving the impurities or burrs extracted by the burring rollers 5 and 5'.

The first three members 3, 4 and 5 are given a relatively slow speed so as to form a first group working at a slow speed.

15 The next following three members 3', 4' and 5' are given a relatively high speed so as to form a second group working at an increased speed, the driving pulleys of these members having suitable diameters for this purpose.

20 The two burring mechanisms, in series arrangement, are interposed between the breasting roller 1 and the carding cylinder 2. In the first mechanism, or group of associated burring elements, the bristle roller 3 operates to convey the material being treated from the breasting roller 1 to the crushing roller 4, which coacts with the beating roller 5 to eliminate the extraneous matter. The beating roller 5 contacts with the associated crushing roller 4 between the bristle roller 3 and 25 30 the bristle roller 3' of the second burring mechanism. In the second burring mechanism, the bristle roller 3' transfers the material from the crushing roller 4 to the crushing roller 4', which coacts with the beating roller 5' to eliminate the remaining extraneous matter. The beating roller 5' contacts with the associated crushing roller 4' between the bristle roller 3' and the transfer roller 6, which operates to convey the material, freed from the extraneous matter, to the carding cylinder 2 for further treatment.

40 Means, well known in the art, are provided for driving the first burring mechanism at a slower speed than the second or succeeding burring mechanism. By driving the first burring mechanism at a comparatively slow rate of speed, the coaction of the beating roller 5 with the crushing roller 4 tends to eject the coarser and heavier extraneous matter without breaking the latter into smaller and finer particles, which would remain in the fiber being treated. Also, owing to the comparative slower speed of rotation of the beating roller 5, there would be less danger of fracture of the roller blades striking the heavier and coarser material.

45 50 55 After the treatment of the materials by the first burring mechanism, it is conveyed by the transfer roller 3' from the crushing roller 4 to the crushing roller 4' of the second burring mechanism to be treated by the beating roller 5' co-

acting with the roller 4'. As the heavier and coarser extraneous matter has been removed, the rollers 4' and 5' are driven at a higher speed than the rollers 4 and 5. This speedier drive of the rollers 4' and 5' in the second burring mechanism is more effective in the elimination of the lighter and finer particles of extraneous matter than is the slower drive of the rollers in the first burring mechanism. After the treatment by the rollers 4' and 5', the material is conveyed by the transfer roller 6 to the carding cylinder 2 for further treatment.

5 10 15 It is clearly understood that without going outside the scope of the invention, alterations, improvements and modifications may be made, while equivalent means may be employed.

I claim:

In a carding machine, the combination of a breasting roller and a carding cylinder; with a series of burring mechanisms interposed between the breasting roller and the carding cylinder to treat successively the material passing from the breasting roller to the carding cylinder; each of said burring mechanisms comprising a bristle roller, a crushing roller for receiving the material from the bristle roller, and a beating roller coacting with the crushing roller for removing extraneous matter from the material carried by the crushing roller; said burring mechanisms being arranged between the breasting roller and the carding cylinder so that the bristle roller of the first mechanism coacts with the breasting roller and with the crushing roller of said first mechanism to convey the material from the breasting roller to said crushing roller, and the bristle roller of the second mechanism coacts with the crushing rollers of both mechanisms to convey the material from the preceding crushing roller to the succeeding crushing roller; a transfer roller for transmitting the material from the crushing roller of the second burring mechanism to the carding cylinder; the beating roller of the first burring mechanism being positioned to contact with the associated crushing roller between the bristle rollers of the respective burring mechanisms, and the beating roller of the second burring mechanism being positioned to contact with its associated crushing roller between the bristle roller of said second mechanism and the transfer roller; and means for driving the respective burring mechanism so that the speed of the first mechanism is comparatively less than the speed of the second mechanism, whereby the slowly driven beating roller of the first mechanism operates to eject the larger and heavier particles of extraneous matter and the more speedily driven beating roller of the second mechanism operates to eject the lighter particles of extraneous matter.

ANTOINE THIBEAU.
